UNITED STATES PATENT OFFICE.

ADAM T. KRAMER, OF BLUFFTON, MINNESOTA.

RAIL-ANTICREEPING DEVICE.

1,014,155.

Specification of Letters Patent.

Patented Jan. 9, 1912.

Application filed October 18, 1911. Serial No. 655,315.

To all whom it may concern:

Be it known that I, ADAM T. KRAMER, a citizen of the United States, residing at Bluffton, in the county of Ottertail and 5 State of Minnesota, have invented certain new and useful Improvements in Rail-Anti-creeping Devices, of which the following is a specification.

This invention relates to fasteners for rail-10 way rails, and more particularly to an anti-creeping device for preventing the longitudinal movement of rails at the ends of inclines, or at track crossings.

The invention has for its objects to produce 15 a simple and efficient fastener which is easily applied to the rail, and which will act to grip the rail both at its lateral edges in a horizontal direction, and in a vertical direction, and at the same time maintain an 20 even bearing against the base of the rail.

Another object of the invention is to provide a device of the character referred to which will automatically tighten its grip upon the rail as the rail contracts, instead 25 of loosening its grip as in devices of this same character heretofore employed.

Other objects of the invention will be made to appear hereinafter.

In the drawings: Figure 1 shows a side 30 elevation, partly in section, of a device embodying the present invention, in position on a rail, with a tie shown in section; Fig. 2 is a sectional plan view of the fastening device shown in Fig. 1, on the line 2-2, 35 Fig. 3; Fig. 3 is a vertical transverse section on the line 3-3, Fig. 2; and Fig. 4 is a perspective view of the wedge member.

As represented herein, the anti-creepers 40 comprises the wedge member 3, and the co-operative supporting member 5, which are respectively arranged to embrace the base of the rail and to be forced into gripping contact with said base, and each other.

The wedge member 3 is composed of a 45 base portion 7 which is of a width to extend beneath the rail base 6, for the entire width thereof and is provided near its left-hand edge, as viewed in Figs. 3 and 4, with an upwardly, and inwardly extending rail-engaging flange 8. The base 7 extends slightly beyond the flange 8 terminating in a rounded rib 10 which is tapered or diminished in thickness from front to rear in a vertical direction, as shown in Figs. 1 and 50 3, and is also inclined to the axis of the rail from front to rear in a horizontal direction to form a wedge, as shown in Fig. 2. The lower face of the base 7 has a slight upward inclination from its left-hand edge to its right-hand edge, as shown in Figs. 3 and 60 4, and the front of said base is provided with a downwardly extending abutment 20 which bears against the tie 21. A longitudinally elongated recess 12 is formed in the rib 10 as shown for a purpose to be explained hereinafter.

The supporting member or shell 5 is composed of a base portion 14 which receives the base 7 of the wedge member, and is inclined laterally from left to right, as seen 70 in Fig. 3, to correspond with a similar inclination on the base 7, and also has an upward inclination from the front edge of the member toward its rear, as indicated by the dotted line 14^a. The member 5 has at 75 one side edge an upwardly and inwardly directed flange 16 which is shaped to fit over the rib 10, and has aligned perforations to receive a locking pin 27 which also passes through the recess 12 in member 3. The 80 opposite side edge of the member 5 has a vertical wall 17, and an inwardly extending flange 18 which engages over the edge of the rail base, the space between that portion of this flange which engages the rail and 85 the underlying face of the base 14 being filled by the edge of the base 7 and the edge of the rail base 6, and being tapered from front to rear, as indicated by the dotted line 14^a.

In order to assemble the parts of the anti-creepers, the flange 8 of the wedge member 3 is hooked over one side of a rail base and the abutment 20 positioned against the face of a tie 21. The supporting member 5 is 90 then slid in position along the rail with its flange 18 over the opposite edge of the rail base, and until the groove inside the flange 16 passes over the rib 10, said rib and groove co-operating to draw tightly together 100 the members 3 and 5 in a lateral direction and thereby, through flanges 8 and 18, and wall 17, gripping the side edges of the rail base between them. By the same operation the relative longitudinal movement of the 105 inclined contacting surfaces on the bases 7 and 14 will effect a vertical wedging action on the edge of the rail base, so that a double wedge is formed, pressing on the edge of the rail and on the bottom of the rail. 110 When the parts have been driven together in position on the rail, any tendency of the

5 rail to "creep" or move on its bed in the direction of the arrow (Fig. 1) will tend to increase the tightness of the grip on the rail, and thus effectually prevent its longitudinal movement. When the parts have been positioned as described, the locking pin 27 is driven into place, there being in practice a slight overlap of the member 5 beyond the member 3 at the rear and the pin occupying 10 the rear end of the recess 12, as shown in Fig. 2, but acting frictionally to maintain the parts tightly in this position under ordinary conditions. In case the rail should contract and shorten faster than the malleable iron shell 5, however, the shell will be moved by the contracting rail a farther distance over the wedge member 3, carrying 15 with it the pin 27 which will then slip along the unoccupied portion of the recess 12 shown in front of the pin in Figs. 1 and 2. By this means, the shortening of the rail as it contracts is applied for automatically tightening the wedging members, and the parts of my rail anchor will thus always be 20 maintained in gripping contact with the rail, notwithstanding variations in temperature.

Changes in the form, proportions, or minor details of construction may be made 25 without departing from the spirit of my invention.

Having thus described my invention, what I claim as new and desire to secure by Letters Patent of the United States is:—

30 1. In a device of the class described, the combination with a wedge having a base to extend wholly beneath the rail base and a lateral flange to engage one edge of the rail, of a supporting member having flanges to 35 fit over a rib on said wedge and the other edge of the rail, respectively, said parts having coöperating wedging surfaces arranged for gripping the rail vertically and horizontally.

40 2. In a device of the class described, the combination with a wedge having a base to extend wholly beneath the rail base, a lateral flange to engage one edge of the rail, an inclined rib beyond said flange, and

an abutment to engage a tie, of a supporting member having a base below the wedge base, a flange to engage the other edge of the rail, and a second flange to fit over said rib.

45 3. In a device of the class described, the combination with a wedge having a rail-supporting base having an inclined surface, a flange to engage one end of the rail, a tie abutment, and a tapering rib inclined horizontally of a supporting member having a coöperating inclined surface, and flanges to 50 engage the other rail edge and said rib respectively, the parts being overlapped whereby when said parts are forced together with a rail between them a gripping force will be applied both vertically and 55 horizontally.

60 4. In a device of the class described, the combination with a wedge having a base, a rail-engaging flange and a tapering, inclined rib provided with an elongated recess, of a supporting member having a base, a rail-engaging flange, a flange having a tapering recess to fit said rib, and aligned perforations, and a locking pin to engage 65 said recess and perforations, whereby upon 70 a contraction of the rail in excess of that of the supporting member the supporting member and wedge will be drawn more tightly into wedging engagement and relative movement between said parts permitted 75 by the elongated recess.

80 5. In an anti-creeper for rails, the combination with the wedge member 3, having the base 7 formed with the lateral and longitudinally inclined surface 14^a, the flange 8, 85 tapering and inclined rib 10 having the recess 12, and the abutment 20, of the supporting member 5 having the base 14 formed to correspond with the surface 14^a, the flange 18, the flange 16 having a recess to fit the 90 rib 10, aligned perforations, and the pin 27 fitting said recess and perforations.

In testimony whereof I affix my signature in presence of two witnesses.

ADAM T. KRAMER.
